[57] CLAIM

The ornamental design for a bill center, as shown and described.

DESCRIPTION

FIG. 1 is a top, front, and left side perspective view of a bill center showing my new design;

FIG. 2 is a reduced top, rear, and right side perspective view thereof;

FIG. 3 is a reduced front elevational view thereof;

FIG. 4 is a reduced left side elevational view thereof, the right side being a mirror image of that shown;

FIG. 5 is a reduced top plan view thereof;

FIG. 6 is a reduced bottom plan view thereof;

FIG. 7 is a reduced vertical cross-sectional view thereof, taken along line 7—7 of FIG. 5;

FIG. 8 is a top, front, and left side perspective view of an alternative embodiment thereof;

FIG. 9 is a reduced top, rear, and right side perspective view of the embodiment of FIG. 8;

FIG. 10 is a reduced front elevational view of the embodiment of FIG. 8;

FIG. 11 is a reduced left side elevational view of the embodiment of FIG. 8, the right side being a mirror image of that shown;

FIG. 12 is a reduced top plan view of the embodiment of FIG. 8; and

FIG. 13 is a reduced bottom plan view of the embodiment of FIG. 8.

The broken-line depiction of the letters and numerals in FIGS. 1 and 8 is for illustrative purposes only and forms no part of the claimed design.
